Arthur C. Brown.

ATTORNEY

UNITED STATES PATENT OFFICE.

HARRY BUDD, OF INDEPENDENCE, KANSAS.

WASHING-MACHINE.

1,226,183.

Specification of Letters Patent.

Patented May 15, 1917.

Application filed November 13, 1915. Serial No. 61,257.

To all whom it may concern:

Be it known that I, HARRY BUDD, a citizen of the United States, residing at Independence, in the county of Montgomery and State of Kansas, have invented certain new and useful Improvements in Washing-Machines; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

15 My invention relates to washing machines, and more particularly to a machine of that class utilizing a dasher for forcing water against and through the clothes being cleansed; the principal object of the present 20 invention being to provide a device of this type with means for containing the clothes so that water may be forced through the entire mass and thereby effectually clean all of the clothes that are contained within the machine.

It is also an object of the invention to provide a dasher which may be adjusted vertically to adapt it for use when the machine is filled to different depths, together with other 30 details of structure, the preferred forms of which are illustrated in the accompanying drawings, wherein:

Figure I is a side elevation of a washing machine constructed according to my invention; part of the housing being broken away to illustrate the interior parts.

Fig. II is a plan view of the machine.

Fig. III is a central vertical section of the same.

40 Fig. IV is a detail perspective of the gearing and its adjustable mounting.

Fig. V is a bottom plan view of the casing.

Referring more in detail to the drawings:

45 1 designates a housing for containing the dasher parts, and which is preferably composed of heavy sheet metal square in cross section and having a flaring lower portion 2 in order to provide for circulation of water, 50 so that the latter may be forced freely through the articles being cleansed and circulate through said articles within the lower portion of the machine.

55 Hinged to one of the upper edges of the housing 1 is a lid or cover 3 having a central collar 4 and preferably provided with a

stiffening rib 5 having a collar 6 registering with the cover collar 4 to form a bearing for the plunger shaft 8.

Located within the housing is a foraminous container 10 which may be of any suitable cross section and preferably consists of a wire cage 11 having side and bottom braces 12, 13 for holding the same against pressure from within when the dasher is lowered 60 against the articles being cleansed; the container being supported within the housing by springs 14 which set on the bottom of the housing and bear at their upper ends upon the bottom braces 13, so that the container is 65 yieldingly supported within the housing.

70 Mounted on the cover 3 is a standard 16 having a vertical slot 17 at its upper end, and slidably mounted within the slot are the bearing portions 18 of a gear plate 19, which 75 latter is held to the standard by the wing nut 21 on a bolt 22 which is fixed to the gear plate and projects outwardly through the slot, a cross bar 23 extending across the slot to engage the standard at opposite sides thereof, so that the wing nut may bear against the bar to tighten the side edges of the gear plate against the face of the standard.

75 Journaled in the lower bearing member 18 is a shaft 25, and revolvably mounted on said shaft is a gear wheel 26 which meshes with a pinion 27 that is fixed on a crank shaft 28 that is revolvably mounted in the upper bearing member 18 and has a crank part 29 provided with a handle 30 whereby the pinion 90 may be revolved to actuate the gear wheel.

80 The gear wheel 26 carries a wrist-pin 32 on which is mounted a pitman 33 having a pin 34 at its opposite end projected through a slot 35 in the upper end of the tubular 95 plunger rod 8.

85 The rod 8 has a plug 37 slidably mounted therein, and fixed to the pitman pin 34 and located within the rod at opposite sides of the plug and bearing against the plug at one end and against a pin 39 and cap 40 on the rod at opposite sides of the plug, are springs 42 which cushion the propelling force of the plug on the rod when the parts are in operation. A plunger 44 is fixed to the lower end of the rod and adapted for vertical movement within the container 10 in order to force water through the articles contained within the container, and which 100 it is desired to clean.

110 In using the device, presuming the parts to be constructed and assembled as de-

scribed, the plunger is moved to the upper limit of its travel and the cover swung back to remove the plunger from the container, so that articles to be cleaned may be placed 5 therein.

When the articles are in the container, the cover is swung back to place and secured in any suitable manner, and the plunger reciprocated vertically with the container 10 by manipulation of the crank; such reciprocatory movement being cushioned by the springs 42, so that should the mass within the container resist the plunger sufficiently, the springs will yield to prevent damage 15 to the mechanism.

As the plunger is reciprocated, water is forced through the articles being cleansed at both the sides and bottom of the container so that all of the articles in the mass 20 are subject to the cleansing action.

After the articles have been cleansed, the cover, with the parts carried thereby, may be swung back to expose the container so that the latter with the articles therein 25 may be removed from the housing or the articles may be removed from the container without taking the latter out of the machine.

It is apparent that if only a few articles 30 are placed within the container, the plunger must be lowered farther than if a great many articles were placed therein. This vertical adjustment is provided for, as

should only a few articles be placed in the container, the plunger may be lowered by loosening the wing nut, lowering the gear plate and again tightening the nut to clamp the plate to its standard at a low elevation; the elevation being varied to suit the quantity of articles within the container.

Having thus described my invention, what I claim as new therein, and desire to secure by Letters-Patent, is:—

1. A washing machine comprising a housing having a flared lower end, a mesh container located within the housing, a plunger having a rod extending through the top of the container, an adjustable support, gearing mounted on the support, and means connecting the gearing with the plunger 45 rod.

2. A washing machine comprising a housing, a cover on said housing, a standard on said cover having a slotted upper portion, a gear plate having guide members projected into the standard slot, a bolt extending through said slot, a nut for attaching the bolt to the standard, a gear wheel and pinion mounted on the plate and meshing with each other, a pitman on the gear wheel, connection between the pitman and the plunger rod, and a crank connected with the pinion, for the purpose set forth.

In testimony whereof I affix my signature.

HARRY BUDD.
